UNITED STATES PATENT OFFICE.

GEORGE F. GILLETTE, OF LOS ANGELES, CALIFORNIA.

INTERNAL-COMBUSTION-ENGINE VALVE.

1,112,786.

Specification of Letters Patent.

Patented Oct. 6, 1914.

Application filed June 5, 1913. Serial No. 771,942.

To all whom it may concern:

Be it known that I, GEORGE FRANCIS GILLETTE, a citizen of the United States, residing at Los Angeles, in the county of Los Angeles, State of California, have invented new and useful Improvements in Internal-Combustion-Engine Valves, of which the following is a specification.

This invention relates to valves for pressure motors of any character; to valves for piston and cylinder engines and particularly for internal combustion engines.

The fundamental conception of my invention consists in the provision of a rotary single plate valve adapted to completely and efficiently control and cause the operation of the motor; and a secondary conception of my invention comprises the provision of a single rotary valve construction for a plurality of cylinders, one valve controlling and causing the operation of a number of cylinders of the engine.

The preferred form of my invention, as I now embody it in mechanical construction, comprises the provision of a single valve for a number of cylinders, up to three or four, or possibly six; and I will herein explain my invention as it is applied to an internal combustion engine of three cylinders and of four cylinders, the other arrangements being easily deducible from these arrangements, and other applications of my valve construction being easily inferred from the following specific descriptions of its application in combination with an internal combustion engine.

There are numerous objects of my invention; but the most important ones may be stated as follows: to provide a simple arrangement wherein the number of parts is reduced to a minimum and wherein simple uniform rotary motion takes the place of the complicated motions now in general use in valve constructions for internal combustion engines; and to provide a valve construction and action which materially increases the effective power which may be obtained from an engine of given dimensions.

Other objects following from or contributing to these main objects will appear throughout the following detailed specification.

I have shown my preferred forms of con-

struction in the accompanying drawings, in which:

Figure 1 is a side elevation showing my invention as applied to a three cylinder engine. Fig. 2 is a central vertical section taken as indicated by line 2-2 of Fig. 1. Fig. 3 is a horizontal section showing the details of the valve construction and taken as indicated by line 3-3 of Fig. 2. Fig. 4 is a top view of the valve arrangement. Fig. 5 is a view similar to Fig. 3 showing the application of my invention to a four cylinder engine and showing various modifications. Fig. 6 is a side elevation of the form shown in Fig. 5. Fig. 7 is a view similar to Figs. 3 and 5 showing the application of a modified form of valve to a three cylinder arrangement. Fig. 8 is a section taken as indicated by line 8-8 of Fig. 7.

In the preferred form of my invention shown in the accompanying drawings, the numeral 10 may designate a suitable crank case, on which the several cylinders 11 are mounted, the crank shaft 12 being mounted in suitable bearings 13 and having thereon, in the form of Figs. 1 to 4, three cranks 14^a, 14^b and 14^c preferably arranged as is best shown in Fig. 2. The cylinders 11 are best set in the general relative positions shown in the drawings, in such manner that their upper or head ends are arranged symmetrically about a central vertical axis, and so that the axes of the cylinders make equal angles with a vertical plane passing through the center of the crank shaft. Each of the cylinders points directly at the crank shaft; that is, the axis of each cylinder intersects the crank shaft axis. The appearance of the cylinders in this arrangement is that of being arranged on a sharp angled V. This peculiar arrangement of the cylinders enables me to serve all three cylinders with a single valve construction, and, at the same time, to have direct, simple and efficient connection between the pistons and cranks. The cylinders are preferably cast close together as a single casting; and at the head ends of the cylinders there is cast a common head plate 20 which forms the base upon which the rotary valve plate 21 revolves. This rotary valve plate is preferably a simple flat plate having therethrough an exhaust port 22 and an intake or inlet port 23; the plate being mounted

upon a suitable valve shaft 24 which rotates in bearings 25 and 26 in the base plate 20 and in the housing 27 which at once forms an enclosure for the valve and forms 5 within it the exhaust and inlet chambers 28 and 29 from which the exhaust is led through piping 30 and to which the carbureted charges are led through piping 31. On the upper end of the valve 10 shaft 24 I preferably provide the driving gear 35 which meshes with a gear 36 on a horizontal countershaft 37, horizontal countershaft being driven through the medium of gears 38 and 39 from vertical 15 countershaft 140 which in turn is driven from the crank shaft 12 through the medium of gears 141 and 142. The arrangement is such that the gear 35, and the valve shaft and valve, travel at one-half the speed 20 of revolution of the crank shaft; and this difference of revolving speed may be introduced in the gearing arrangement at any suitable point. I have preferably shown the gear 38 to be twice the diameter of 25 gear 39, causing the shaft 37 to rotate at half the speed of shaft 140. This gearing arrangement is peculiar to the three cylinder arrangement herein described; it will be shown hereinafter that the rotation ratio 30 depends entirely upon the number of cylinders served by the valve and the number of sets of ports through the valve.

Through each of the heads of cylinders 11, and through the base plate 26 upon which the valve 21 rotates, there extend exhaust and inlet ports 40 and 41 of the general configuration shown in Figs. 2 and 3. These cylinder ports are so designed as to be of ample capacity to allow unrestricted entry and exit of combustible charge and exhaust to and from the cylinders; and, in my present preferred arrangement, I make these valves extend through an angular distance of twenty degrees around the center 45 of the valve shaft 24. The exhaust valves are arranged inside the inlet valve, so as to each be registered in turn by the exhaust port 22 of the valve 21; while the inlet ports 41 are adapted to be registered successively by the valve intake port 23. To prevent leakage under and over the valve I may provide suitable packing rings 42; and for providing sufficient lubrication of the valve I may have a central oil bore or passage 43 leading down through the valve shaft 24, and suitable lateral distributing passageways extending through and under the valve 21, as shown at 44 and 45. The exhaust chamber 28 of the housing 27 communicates at all 50 times with the exhaust port 22 of the valve, while the intake chamber 29 communicates at all times with the intake port 23.

The periods during which the ashore and intake ports are opened and closed may be regulated as desired; but in my judgment

Form of motor I have assumed to have the intake open through 200 degrees of rotation of the crank shaft and to have the exhaust open during 225 degrees of crank shaft rotation between the closing of the exhaust 70 for one cylinder and the opening of the intake for that cylinder. I allow 140 degrees of crank shaft rotation for the explosion period and 150 degrees of crank shaft rotation for the compression period. The intake period will commence with the crank shaft 10 degrees rotated from its uppermost position and the intake will finally close after the shaft has rotated to a position 30 degrees beyond its lowermost position, making the intake period 200 degrees of crank shaft rotation. The compression period begins at the closing of the intake period and ends with the crank again in its uppermost position, having made one complete revolution from a position 10 degrees before the beginning of the intake period. The explosion period then occupies 140 degrees of rotation of the crank shaft; and the exhaust period then occupies the rotation of the crank shaft through 225 degrees until the crank shaft is five degrees past its uppermost position. Five degrees further revolution brings the opening of the intake and the cycle is repeated. Since I have 95 made the cylinder ports 40 and 41 of twenty degrees extent around the valve shaft axis,

any given point on one of the valve ports will take a period of forty degrees of crank shaft rotation to pass completely over each cylinder port. Consequently, each of the valve ports must be of an angular extent around the valve axis measured by half the difference between the total angular crank shaft period of intake and exhaust opening and the crank shaft period of forty degrees consumed by any point on the valve passing completely over any one of the cylinder ports. Thus, I have shown the exhaust port 22 being of approximately 82 degrees extent about the shaft 24, while the intake port 23 is shown of 80 degrees extent around the shaft. The gearing arrangement of the valve causes it to rotate in the direction indicated by the arrow causing the valve exhaust port to register with a cylinder exhaust port immediately preceding the registry of the valve intake port with the intake port of the same cylinder. As before expressed, I arrange to have a period of five degrees of crank shaft rotation, being $\frac{2}{3}$ degrees of valve rotation, between the closing of the exhaust and the opening of the intake, to prevent leakage from the intake to the exhaust chamber. As illustrated in Fig. 3, it will be seen that the exhaust port 22 has just passed over the cylinder exhaust port 40 of the cylinder 11, at the lower right hand side in Fig. 3 and is within five degrees of closing the exhaust, and that the intake port 23 is within ten de-

grees movement to register with the cylinder intake port 41 of the same cylinder; the piston 9^b of this cylinder 11^b is at its uppermost point, the crank 14^b and the connecting rod 8^b being in a straight line. The exhaust is within five degrees of completely closing; and the intake is within ten degrees of beginning to open. Further rotation of the valve will cause its exhaust port 22 to next reach the cylinder exhaust port 40 of cylinder 11^c, the exhaust for this cylinder beginning then to open when the crank 14^c is within 40 degrees from its lowermost position; that is, within 40 degrees of the position in which the piston is at its lowermost point of stroke. Another one-third revolution of the valve, or two-thirds revolution of the crank shaft, will bring the valve exhaust port 22 into registry with exhaust port 40 of cylinder 11^a; and it will be seen that such an amount of revolution will carry the crank 14^a to a position 40 degrees before coming to its lowermost position, or where its piston is at the lowermost point of its stroke. The closing of the exhaust, and the opening and closing of the intake for each of the cylinders will follow in the same sequence, and, at the same time, a complete cycle of valve operation will take place for each two revolutions of the crank shaft. It is thus seen that each cylinder performs a complete cycle of operation upon every two revolutions of the crank shaft, and that there are three explosion periods in the whole engine during each two revolutions of the crank shaft.

I have first explained my three cylinder arrangement because of the simplicity of my valve construction thereto, and for the reason that the principles involved are fundamentally those which are involved in the adaptation of my valve to any number of cylinders. A one or two cylinder arrangement is made by simply taking two or one cylinders away from the three cylinder arrangement; the four cylinder arrangement will be described; any arrangement containing a multiple of these numbers of cylinders may be had by mere duplication, for instance a six cylinder engine being only two three cylinder or three two cylinder engines aggregated.

55 It is seen that in the three cylinder arrangement there is sufficient angular space between the adjacent cylinder ports to allow of intake and exhaust ports of sufficient angular extent to have the exhaust and intake periods of sufficient angular extent. However, in the application of my valve to an engine of four cylinders or 60 more, it is necessary, or at least desirable, to supply the valve with a plurality of sets of ports and to rotate the valve correspondingly more slowly. For application to an engine of four cylinders, the simplest form 65 of valve contains three sets of valve ports;

in general, if the number of cylinders be even then the number of sets of valve ports must be odd to obtain uniformly successive firings of the different cylinders; and, on the same general principle, if the number of cylinders is odd then the number of sets of valve ports must be even. These general observations do not apply, of course, to an arrangement where one set of valve ports will suffice, as with an arrangement of three cylinders or less. The general principles and particular reason underlying these features of my construction will become more readily apparent in the description of my valve construction as applied to a four cylinder arrangement. In the application of my valve construction to a four cylinder arrangement, as I have shown in Figs. 5 and 6, I have indicated the four cylinders 11^a, 11^b, 11^c and 11^d arranged with their head ends symmetrically around the vertical axis of vertical valve shaft 24^c; the arrangement being practically the same as in the three cylinder arrangement except that there are four cylinders to be arranged about the central vertical axis instead of three as before. The angular distance between successive cylinder ports as measured about the vertical axis of the valve shaft 24^c, is only 90 degrees; and would be only 180 degrees of crank shaft rotation if the valve were rotated at one-half the speed of the crank shaft and if the valve had only one set of ports as in the three cylinder arrangement. 180 degrees of crank shaft rotation is, as has been before explained, less than the total period of opening of either of the intake or exhaust; and, under the conditions of the single ported valve, either the intake or the exhaust valve would at certain times register with two successive cylinder ports. This would be objectionable on account of interconnecting the cylinders. It consequently becomes necessary to rotate the valve at a slower speed so that the extent of the valve ports about the central valve shaft may be made less than before. In order to allow the valve to rotate at a slower speed and to have the ports of each cylinder opened and closed during each two revolutions of the crank shaft, it is necessary to increase the number of ports in the valve. It is necessary that the cylinder ports be arranged symmetrically around the vertical axis; and it is also necessary that the valve ports be arranged symmetrically around that axis, both of these conditions being requisite to uniform successive operation of the different cylinders. It is immediately seen that if the number of valve ports is increased to any even number of sets, then two opposite cylinders, of the four, will be performing their cycles simultaneously and in the same order.

For instance, if the number of sets of valve ports are to be increased to two, then instead of the four cylinders firing in regular successive order, there would be simultaneous firing of two opposite cylinders and then simultaneous firing of the other two opposite ones. This would make the arrangement practically the same in effect as a two cylinder engine. Consequently, it is necessary to increase the number of valve ports to an odd number of sets, and the simplest arrangement for the four cylinder engine is a valve with three sets of ports symmetrically arranged at the axis of valve shaft 24. With a valve arranged in this manner, it is seen that the valve will travel one-third of a revolution between successive passages of its exhaust or inlet port over the ports of any one cylinder. This one-third revolution of the valve must consequently correspond to two whole revolutions of the crank shaft. In this arrangement, then, I have shown the valve 39° to be of one-third the pitch diameter of gear 35° while gear 39° is one-half the pitch diameter of gear 23°. Shaft 40° is rotated at even speed with the crank shaft, as in the form hereinbefore described, the net result being that the valve 21° is rotated at one-sixth the speed of the crank shaft. It will be seen that, beginning with the valve in the position shown in Fig. 6, the cylinder 11° will first enter upon its intake period, the cylinder 11° being just about to close its intake period. Within a period corresponding to a one-sixth revolution of the crank shaft, or one-twelfth revolution of the valve, the intake to the cylinder 11° will be open; then within another similar period the intake to the cylinder 11° will be open and within another period the intake to the cylinder 11° will be open. Thus the cylinders will pass through their cycle in regular successive order; and each cylinder will pass through a complete cycle for each two revolutions of the crank shaft.

In the form of my arrangement shown in Fig. 5, I have shown the cylinder and valve intake ports of equal angular extent, and the exhaust ports of equal angular extent than the valve intake ports. I have shown this arrangement merely to indicate the flexibility and adaptability of my system to any desired arrangement of the various portions of the cylinder cycle, and to any desired arrangement of the intake and exhaust openings. In the arrangement shown in Fig. 5 it will be seen that the intake and exhaust will each be fully open during only an instant of their respective opening periods, due to the fact that the valve and cylinder ports are of equal size and that consequently the valve

will begin to close at the instant at which they become fully open. This is the condition which obtains in any case of valve operated by a cam or eccentric; and is the particular condition under which all poppet valves and slide valves operate.

In Fig. 3 I have shown the valve ports of valve 24 rotated angularly from the cylinder ports, and consequently the valve and exhaust will each be fully open during a longer portion of their respective periods. Illustrating the complete open period of the exhaust in 120 degrees of crank shaft rotation, it requires 60 degrees of crank shaft rotation from the time the exhaust begins to open until it is fully opened; but it also requires 60 degrees of crank shaft rotation to close the exhaust. Thus during 120 degrees of crank shaft rotation the exhaust is fully open, this period of full operation being more than three-fifths of the total exhaust open period. It will be seen that the duration of intake and exhaust opening may be varied between a limit on one hand where the valve and cylinder ports are equal to a limit on the other end where the cylinder ports are made as small as they can be without restricting the passage of air.

In order to hold the valve 21 tightly against the base plate 20 I have shown two forms of arrangement. In Figs. 2, 3 and 4 I have shown the head or cap 27 provided with a hinge 106 at one side and with hold-down bolts 101 on the other side. This arrangement provides for lifting the head and suspension of the valve. In Figs. 3 and 4 I have shown an arrangement comprising holding down bolts 101 and adjustable set screws 102. These screws 102 are adjustable in the cap or head 27 and their lower ends rest upon the base plate 20 so as to support the head at a suitable distance above the base plate. The screws 102 may be adjusted so as to bring the head down to a point where it will press the valve tightly, but movably, into engagement with the base plate. This arrangement provides for a tight joint between the valve and the base plate, providing for operation of the engine without leakage of any kind.

I have shown a suitable ignition controlling arrangement consisting principally of a rotatable carrier 100 arranged to be relatively adjustable about the valve shaft 24 above the head 27. This carrier 100 supports three contacts 121 which may be connected by any suitable system of wiring with the ignition apparatus of the several cylinders. A suitable rotating arm 122 is mounted to rotate with the shaft 24 and carries a contact 123 which may or may not be grounded on the frame of the engine. This contact 123 changes the position of the contacts 121 during the rotation of the valve shaft, causing the closure of circuits which cause 130

ignition of the charges in the various cylinders at appropriate times. The carrier 120 may be adjusted in position through the medium of its projecting arm 124 to which 5 operating rods, etc., may be attached; and the position of the carrier 120 and of the contacts 121 may be indicated by a pointer 125 traveling over suitable angle designations 126; the arrangement being such that 10 the degree of advance or retard of ignition may be easily known.

In Figs. 7 and 8 I have shown the application of a modified form of valve to such a three cylinder arrangement as is shown in 15 Fig. 1. This modified form of valve accomplishes many of the results of the preferred form hereinbefore described. It is a valve in a single piece rotating uniformly and supplies a plurality of cylinders; the 20 main difference between the modified valve and the one originally described being that the ports, instead of extending through the flat plate of the valve, extend through a raised rim of the valve. The cylinder ports, 25 instead of extending through a flat base plate upon which the flat plate revolves, extend through the cylindrical walls of inclosing casing 133 against which the raised edge or periphery of the modified form of valve 30 revolves. In these figures I have shown the extent of the various ports to be the same as in the Fig. 3; and I shall therefore herein explain only the points in which this modified form differs from the form first described. The valve 21^h is preferably driven 35 from below by a valve shaft 24^h. The valve 21^h is composed of a central horizontal web 130 and upper and lower rims or peripheral portions 131 and 132. The exhaust and intake ports 22^h and 23^h extend through the 40 rims 131 and 132, and are adapted to register with ports 40^h and 41^h extending through the cylindrical wall of the inclosure casing 133. The ports 40^h and 41^h lead into the 45 various cylinders 11^h, 11ⁱ and 11^j and the valve 21^h is rotated at one-half the speed of the crank shaft to which the pistons in the 50 cylinders are connected. The cycle of operation is exactly as hereinbefore explained for the plate form of valve in combination with three cylinders.

From the foregoing the relative simplicity and efficiency of my valve construction will be readily apparent. I have utilized none 55 of the ordinary cams, followers, push rods, rocker arms and the various other parts usually used for puppet valves; but on the other hand I utilize a simple system of uniform rotary motion which, in combination 60 with the simple rotary plate valve, makes possible the positive and accurate setting of the valve. Once the valve with its ports and the cylinder ports have been accurately designed and constructed to obtain intake, 65 compression, explosion and exhaust periods

of the most efficient proportions, it is impossible to change the timing when once thus set. Should the valve require re-setting, that operation is extremely simple, involving only the re-setting of one valve 70 for a number of cylinders and involving the setting of that one valve only with regard to one given position. For instance, the piston of one cylinder may be set in its uppermost position, and the valve may then be set 75 so that the exhaust for that cylinder is within five degrees (measuring by crank shaft rotation) of closing; the whole valve is then accurately set for the whole of the cycle for 80 all the cylinders. It is also seen that the opening periods and the periods of full opening and the areas of opening for the intake and exhaust, respectively, of the several cylinders must be exactly equal; for the conditions as applied to one cylinder are 85 exactly duplicated in any of the others. This is in contra-distinction to a valve construction of the double sliding plate or double sliding cylinder type operated by cams or eccentrics. For the reason that cams or 90 eccentrics produce an irregular (generally a sine curve) motion, it is an arduous task to design and regulate all of the valve opening periods and areas to be exactly the same. In a valve operated by cams or eccentrics, 95 there are three conditions which must be accurately met in setting each valve, or each part of each valve. The time of opening must be set, the full open area must be made a certain amount, and the time of closing 100 must be set. On a six cylinder engine having, say, a double plate valve there are twelve valve ports with cams and connecting rods each of which must be set for each of the above mentioned conditions as compared with 2 or 1 on mine. The distinctive feature of my valve, as compared with such a valve as above explained, is its simplicity 105 and accuracy.

The features I wish to particularly emphasize in this application and in the following claims are: (1) the arrangement of the cylinder ports and valve ports, in a flat plate valve of the character described, so that the inlet port set and exhaust port set 110 are entirely independent of each other—that is, so that the valve inlet port serves the cylinder inlet port alone, and the same of the exhaust ports; (2) the arrangement which enabled my valve to serve a plurality 115 of cylinders, with the cylinder ports arranged symmetrically about the valve axis, and preferably with the cylinder heads also so arranged.

Another feature which I would herein 120 emphasize is the ease with which my valve may be removed, replaced, or repaired. In common with all plate valves, as distinguished from cylindrical puppets, my valve has the advantage that wear improves the 125 130

surfaces and increases securitv against leakage, whereas the two classes, above mentioned, by wear, constantly grow more inefficient.

5 Having described a preferred form of my invention, I claim:

1. In combination with a ported cylinder and a piston therein and rotating mechanism driven by the piston, a stationary flat base plate at the cylinder head through which base plate the cylinder intake and exhaust ports extend, a single circular plate valve rotatable on said base plate and having exhaust and inlet ports extending therethrough adapted to register respectively with said cylinder exhaust and inlet ports, the exhaust port being closer to the rotation axis of the valve than the inlet port, a central drive shaft for said valve, a head 15 mounted over the valve having concentric chambers connecting with the exhaust and intake ports of the valve, the intake chamber surrounding and enveloping the exhaust chamber, induction and exhaust pipes leading to and from the intake and exhaust chambers, the valve shaft projecting through the chambered head, a gear on the upper end of the valve shaft, and rotative connecting means between said gear and the 20 rotating mechanism driven by the piston.

2. In combination with a plurality of cylinders each having intake and exhaust ports, pistons in said cylinders, and rotating mechanism driven by said pistons, a stationary flat base plate through which the ports of all the cylinders extend, a single rotating plate valve arranged on the base plate having intake and exhaust ports therethrough adapted each to register successively with the 35 respective intake and exhaust ports of all the cylinders, and means to uniformly rotate said valve co-operatively with said rotating mechanism.

3. In combination with a plurality of cylinders arranged with their head ends symmetrically about a central vertical axis, pistons in said cylinders, and rotating mechanism driven by said pistons, a stationary plate extending over the heads of all said cylinders, there being ports leading through said plate to said cylinders, said ports arranged symmetrically about said vertical axis, a single plate rotating valve over said head plate having intake and exhaust ports 50 extending therethrough adapted each to successively register with the respective intake and exhaust ports of all said cylinders, and means to uniformly rotate said valve co-operatively with said rotating mechanism 55 driven by the pistons.

4. In combination, a crank case, a crank shaft therein, a plurality of cylinders arranged symmetrically with reference to a vertical axis, pistons in said cylinders connected with said crank shaft, a common

stationary head plate for all said cylinders, induction and exhaust ports for said cylinders leading through said common head plate, the ports being arranged symmetrically about said vertical axis, all the 70 induction ports being at a common distance from said vertical axis and all the exhaust ports being at another common distance from said vertical axis, a single plate rotary valve upon said head plate having inlet and exhaust ports leading therethrough adapted to successively register with the respective inlet and exhaust ports of all said cylinders, a head above said valve having concentric chambers therein connecting with the intake and exhaust ports thereof, a drive shaft for the valve extending upwardly through said head, and gear mechanism for rotating said shaft co-operatively with the crank shaft. 80

5. In combination, a crank case, a crank shaft therein, a plurality of cylinders mounted on the crank case symmetrically with reference to a vertical axis, pistons in said cylinders connecting with the crank shaft, a common head plate covering the heads of all said cylinders, intake and exhaust ports for said cylinders leading through said head plate, said ports being arranged symmetrically about said axis, and the exhaust ports 90 being arranged closer to said axis than the intake ports, a rotary flat plate valve mounted on the head plate to rotate about said axis having intake and exhaust ports leading therethrough adapted to respectively register successively with the intake and exhaust ports of all the cylinders, the valve exhaust port being arranged closer to said axis than the intake port, a head above the valve having concentric chambers therein connecting 100 with the exhaust and intake ports of the valve, the intake chamber surrounding and enveloping the exhaust chamber, a drive shaft for the valve projecting upwardly through said head and gearing causing the 110 respective rotation of the valve shaft and the crank shaft.

6. In combination with a plurality of cylinders arranged with their head ends symmetrically about a central vertical axis, a stationary head plate for said cylinders, there being exhaust and inlet ports for each cylinder leading through said plate arranged symmetrically about said axis with the exhaust and inlet ports arranged at different radial distances from said axis, and a flat plate valve rotatable on said axis on the head plate, said valve having exhaust and inlet ports therein adapted to register with the respective cylinder exhaust and inlet ports. 115

7. In combination with a plurality of cylinders, a valve mechanism comprising a valve base having ports leading to the several cylinders, a rotatable valve having a port adapted to register with said base ports, 120

- said base ports being arranged in common circular paths of travel about the axis of the valve so that ports of the several cylinders will be successively registered by valve port.
- 5 8. In combination with a plurality of cylinders, a valve mechanism comprising a base with ports therein leading to the several cylinders, said ports being arranged symmetrically about a common axis, a valve rotatable on said axis and having a port therein adapted to successively register with the ports of the several cylinders, the arrangement being such that the valve port serves each of the cylinders in succession.
- 10 9. In combination with a plurality of cylinders, a valve mechanism comprising a base

with ports therein for the several cylinders, said ports being arranged in common circular paths of travel about a common axis, a valve rotatable about said common axis and having a plurality of ports, each of said ports adapted to successively register with the ports of the several cylinders, so that each valve port serves each cylinder in common with the others.

20

25

In witness that I claim the foregoing I have hereunto subscribed my name this 31st day of May 1913.
